UNITED STATES PATENT OFFICE.

WILLIAM S. EASTON, OF SEATTLE, WASHINGTON.

ROTARY PUMP.

1,264,032.

Specification of Letters Patent. Patented Apr. 23, 1918.

Application filed January 17, 1917. Serial No. 142,941.

To all whom it may concern:

Be it known that I, WILLIAM S. EASTON, a citizen of the United States, and resident of the city of Seattle, county of King, and State of Washington, have invented certain new and useful Improvements in Rotary Pumps, of which the following is a specification.

My invention relates to pumps of the type which employ rotary impellers. My invention comprises certain features of construction by which the facility of operation of the pump is improved and the details of construction simplified and also improved. My invention comprises the parts and combinations thereof which will be described in the specification and then particularly pointed out in the claim. The accompanying drawings show my invention in the form of construction which is now preferred by me.

Figure 1 is a top or plan view of the pump, showing one bar broken away to better illustrate the construction.

Fig. 2 is a side elevation of the same pump.

Fig. 3 is a transverse section on the line 3—3 of Fig. 1, the same being through the impellers and the inlet and discharge ports. Fig. 4 is a section on the line 4—4 of Fig. 1, or through the bearings at one end.

Fig. 5 is a longitudinal section taken on a vertical plane through one of the bearings.

With my pump I employ two shafts, 1 and 2, placed adjacent each other and parallel, and upon these are mounted two impellers, these being provided with cylindrical portions which turn substantially in contact with each other, of which one impeller is provided with projecting vanes, while the other is provided with recesses adapted to receive and pass said vanes. The two shafts are connected for synchronous rotation by means of intermeshing gears 7 and 70, placed on one end thereof.

The impellers are of substantially the cross section shown in Fig. 3. The impeller 10 has vanes 11 projecting therefrom, having four in number as shown. The impeller 20 has recesses 21 of such size and shape as to receive and pass the vanes 11 of the other impeller. Two such recesses are shown. The gears 7 and 70, which are secured to the same shafts, bear a ratio of two to one, so that the impeller 20 turns at twice the rotative speed of the impeller 10.

The two impellers are inclosed within a casing 3 which is of such size as to fit closely, but not tightly, against the outer rotative surfaces of such impellers. I prefer to have this connection as tight as may feasibly be made without having actual contact. While this may produce a slight leakage backward in the pump, it will reduce friction losses.

Casing 3 has a discharge passage 32 and an inlet passage 31. The shafts 1 and 2 are preferably placed with the shaft 2, which carries the smaller of the two impellers, at a slightly higher level than the other shaft 1 and the inlet passage 31 enters the impeller chamber from a horizontal direction immediately below the impeller 20, and has its lowermost edge sufficiently above the lowermost point of the impeller chamber, to provide a pocket 30, in which water will be trapped when the pump is stopped. The purpose of this is to insure that the pump will at all times contain a sufficient amount of liquid to insure priming. The shafts, on leaving the impeller chamber, pass through stuffing boxes 33.

The pump casing is centrally placed upon a base 9, and upon the ends of the base are secured pillar blocks or bearing supports for the shafts which supports are spaced away from the pump casing. By reason of this arrangement, I am enabled to employ stuffing boxes 33 and thereby prevent leakage about the shafts. The spacing of the bearings 4 from the pump casing is enough to permit withdrawal of the followers 34 for repacking. Providing the additional bearings 4 at each end of the shafts, these being independent of the bearings in the pump casing, relieves the latter bearings of considerable strain and, therefore, aids in keeping a tight joint about the shafts.

The bearings, on the ends of the shafts are, to a certain extent, special in construction. Such bearings are shown by the two sections of Figs. 4 and 5. The pillar block, or stand, 4, is made hollow to act as an oil chamber for the reception of oil with which to lubricate the bearings. The lower side of the bearing is provided with a hole, or holes, through which may pass the two sides of a lubricating chain 5, which is hung upon the bearing and which has its lower end depending into the oil in the chamber. The operation of this device is similar to that of the ordinary chain lubricator.

The shaft at the end of the bearing, which

is toward the chamber 3, is preferably provided with grooves cut therein after the style shown at 12 in Fig. 5 and Fig. 1. The stand 4 is provided with outwardly extending flanges 41 which provide a slight chamber which embraces the threads 12 cut in the shaft. This chamber is provided with a storage channel 42 which connects with the chamber 40 in the base of the bearing. Any oil which works through the bearing in this direction is stopped by the slight flanges 12 and whatever drips therefrom is immediately drawn back into the oil storage chamber 40.

15 At the other side of the bearing the stand 4 has flanges 6 which form a case for the gears. The gears 7 and 70 are secured to this end of the two shafts and intermesh. The lower edges of one of these gears dips 20 into the oil in the storage chamber, thus maintaining lubrication upon the wheels at all times. The oil which comes from this end of the bearing is sufficient to maintain lubrication for the gears. The bearing is 25 covered by a cap 43 which has, as a part thereof, a flange 60 which forms the upper half of the gear case and also a flange 44, which forms the upper half of the oil in-

tersecting chamber at the other end of the bearing. Upon one of the shafts a pulley 39 wheel 8, or any other equivalent means for driving the pump, is connected.

I have found that the slight amount of water which would be trapped in the priming pocket 30 is sufficient to insure priming and prompt starting of the pump. Without this a pump, in order to work under suction, would have to be primed every time it is started.

What I claim as my invention is:

A pump having two intermeshing rotative impellers and a casing inclosing said impellers, said impellers being located to bring one shaft at a slightly higher level than that of the other, the casing having a discharge opening at its upper side and an inlet passage extending horizontally from its lower side beneath the higher of said impellers, the bottom line of said inlet passage being above the bottom side of the chamber containing the lowermost impeller to thereby provide a priming pocket.

Signed at Seattle, Washington, this 12th day of January, 1917.

WILLIAM S. EASTON.
